UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,018,477.

Specification of Letters Patent. Patented Feb. 27, 1912.

Application filed October 26, 1907. Serial No. 399,818.

To all whom it may concern:

Be it known that I, MATTHIAS BROCK, a citizen of the United States, residing at Boston, in the county of Suffolk and Commonwealth of Massachusetts, have invented certain Improvements in Lasting-Machines, of which the following description, in connection with the accompanying drawings, is a specification, like reference characters on the drawings indicating like parts in the several figures.

This invention relates to machines for lasting shoes and particularly to machines of the type known as "bed" lasting machines in which a last, usually in inverted position, is rested upon a support while the upper materials are worked into lasted position at one or both ends of the shoe by end lasting devices or end lasting mechanisms.

For the best results the end lasting mechanisms should face squarely toward the end portions of the last to be acted upon or in the direction of the median line of the adjacent end portion of the last. These end lasting mechanisms used at the heel usually include a heel band which is depended upon to clamp the upper materials about the heel portion of the last and especially to force the end portions of the heel stiffener up to the last. These mechanisms also generally include, both at the heel and the toe, wiper plates which are employed for wiping the upper over the last into position to be secured. In lasting welt shoes it is important that the toe lasting plates fit over the last so that they will force the upper firmly up against the lip or shoulder of the inner sole to which the upper is to be permanently secured by a subsequent operation.

The lasts in general use at the present time are formed with more fullness at the outer side of the forepart and the heel part than at the inner side. The excess of fullness on one side of the last as compared with the other side, which is commonly called the "swing" of the last, is formed on the left side of a left last and on the right side of a right last. Therefore end lasting devices which are properly arranged in accordance with the swing of a right last

to clamp the heel stiffener at the full side and the hollow side of the heel, and to force the upper against the lip of the innersole at the full side and the relatively straight side of the toe, will not be properly arranged for the corresponding left last. The heel band will not clamp the counter against the hollow side of the left last nor will the toe wiper plates force the upper up to the lip of the innersole on the relatively straight side of the forepart without overriding and breaking down the lip on the full side. Another difficulty is found with the wiper plates at the heel, which, in order to wipe the upper over into position to be tacked on the hollow side of the heel have to be forced over beyond the nailing line on the full side. This makes it necessary for the operator, after tacking the heel seat at the hollow side of the last, to stop and back the wipers off from the full side before he can tack that side.

An object of the present invention is to provide a lasting machine of improved construction in which the end lasting mechanisms shall be arranged for relative movement to enable them to face squarely toward and act properly upon the heel and toe portions of both right and left crooked lasts.

I have discovered that a machine can be adapted to act properly upon the heel and toe of both a right and a left crooked last by moving only one of the end lasting mechanisms provided the movement takes place about a suitably located center. This center I have ascertained may be found at or near the point of intersection of the median lines of the forepart and heel part of the last. These median lines (running from the rear end of the last forwardly midway between the sides of the heel and from the forward end of the last rearwardly midway between the sides of the toe) intersect in lasts now in general use at or near the rear part of the ball or the forward part of the shank. In a left last the median line of the heel part extends obliquely toward one side of the last with relation to the median line of the forepart from the point of intersection of the two lines while in a right shoe the median

line of the heel part extends obliquely toward the other side of the last from this point. Therefore by moving the heel lasting mechanism laterally about this point as a center, in one direction for a left last and in the other direction for a right last, said mechanism may be positioned properly for both a right and a left last, or a pair of crooked lasts. While for the best results the end lasting mechanism should be moved about a center located approximately at the point of intersection of these median lines it may be that some of the advantages of the invention might be secured if the center of movement were otherwise located and the invention includes in its broadest aspect a movement about a center so located that the end lasting mechanism may be positioned to act uniformly along the end part of the last in the direction of the median line of such part, irrespective of the "swing" or angular relation of the median lines of the fore part and the heel part of the last.

A very important feature of the present invention consists in an end-lasting mechanism, or other mechanism adapted to act upon the end portion of a last, which is constructed and arranged to move laterally of the last about a center located under the last at a substantial distance from the ends of the last and preferably at or near the point of intersection of the median lines of the heel part and the fore part of the last. If the heel-lasting mechanism be arranged for example, for movement about a center so located the toe-lasting mechanism may be stationary and arranged to face squarely toward the rear or, in other words, have its middle line in the middle line of the machine. The last, whether for a right or a left shoe, will then be positioned with the median line of its toe portion in the middle line of the machine and the heel-lasting mechanism will be moved laterally about the point of intersection of the median line of the toe part and the heel part toward one side for a right last and toward the other side for a left last. Such an embodiment of the invention is shown in the drawings.

Preferably and in accordance with a further feature of the invention a rest for the heel end of the last will be arranged for movement about a similarly located center to adapt it to give support to the heel part of a right or a left crooked last the fore part of which may be sustained in a fixed position. As shown, the heel support and the heel-lasting mechanism are operatively connected and move together about the same center. In such movement of the heel support, however, the shoe actually pivots about a point at or near the toe end of the last where it is more or less confined between the usual toe wipers and is sustained upon a toe rest which is preferably capable of move-

ment transversely of the machine to accompany the shoe in its lateral movement as will be later explained.

It will therefore be understood that a further feature of this invention is found in the provision for differential adjustment of the last and an end lasting mechanism, as for example, of the heel lasting mechanism about the pivot at the intersection of the described median lines and of the last simultaneously about the more remote center at or near its toe end. As herein employed this differential adjustment serves to move the heel lasting mechanism in the arc of a smaller circle than that in which the heel end of the last is moved and thereby to set said lasting mechanism into symmetrical relation to the median line of the heel portion of a crooked last.

A further feature of the invention consists in novel means for limiting the transverse movement of the heel-lasting mechanism. This means consists in limiting devices which are adjustable together toward and from the middle of the machine and in the illustrated construction they determine the extent of movement of both the heel support and the heel-lasting mechanism.

Another feature of the invention is found in means for automatically locking the laterally movable parts at the limits of their movements. As shown, this means comprises a device movable with the laterally movable parts and arranged to coöperate with the limiting device toward which they are moved in any position of said limiting devices.

One advantage of this invention is found in the fact that the lasting mechanisms are or may be maintained in their laterally adjusted relations to the last during the lasting operation. The heel band of the heel-lasting mechanism will thus act with certainty to clamp the upper and heel stiffener against the hollow side of the last as well as against the full side, while the heel wiper plates will overlie the heel seat the same distance on both sides so that the operator can tack all the way around the heel seat without having to back off the wipers. It is also of importance that the toe wiper plates are rigidly held in their lateral relation to the last because they will then close over the last bottom the same distance on both sides of the shoe for forcing the upper up to the lip of the innersole and will not be displaced if one plate should encounter more resistance than the other.

It is sometimes found that an irregularity exists in a shoe which makes it desirable to adjust the toe-lasting mechanism laterally. For example, the lip on the innersole may be formed farther from the edge of one side of the innersole than from the other side in a particular case or in successive innersoles.

In accordance with another feature of this invention provision is made for adjusting the toe-lasting mechanism laterally after the shoe has been clamped in the machine or before the shoe is jacked, as may be desired. This adjustment is supplemental to the adjustment effected by the movement of the heel lasting mechanism and it is not anticipated that it will often be required. As shown, this supplemental adjustment is made in a curved path and takes place about a center which is separate from the center of movement of the heel-lasting mechanism and which is herein shown as located for convenience under the toe-lasting mechanism, but near to the toe of the last. Manually operated devices in the form of a screw and rack are provided by which the adjustment of the toe-lasting mechanism can be effected at any desired time and the mechanism maintained in its adjusted position.

Another feature of the invention is concerned with the construction and arrangement of the end-lasting mechanism and its actuating means. This is shown in connection with a heel-lasting mechanism which includes a band or clamp to embrace the heel portion of the shoe and clamp the upper materials to the side faces of the heel portion of the last, and also devices such as wiper plates for forcing the marginal portions of the upper over the last bottom into position to be secured to the innersole. The heel band is normally open to its full width, as are also the wiper plates in order that the machine may be ready to receive the largest last for which it is adapted. In the machine shown the last is jacked or adjusted and fastened in position to be operated upon by lifting it to an appropriate level and then closing the heel band about the heel end of the last in the usual way. In accordance with this feature of the invention, the wiper plates are operatively connected with the heel band or its actuating mechanism so as to be automatically advanced from their open position when the heel band is closed. Preferably the wiper plates are also connected with a hand lever or other operating member by which they may be given movements independently of the band and in the illustrated embodiment of the invention the plates are automatically moved up to or slightly over the edge of the shoe and thereafter are actuated by the independent operating member to overwork the upper as, in the judgment of the operator, the conditions presented by each shoe may require. One advantage of thus automatically advancing the wipers is that the operator is relieved of a portion of the movement otherwise required in subsequently manipulating them. The operating member is herein shown as a hand lever which, by the auto-

matically effected movement of the wipers, is brought from a position where it is out of the way of the workman into a position where it can be conveniently grasped by him for the manual manipulation of the wipers. 70

As will be understood from the foregoing, the shoe is or may be positioned or centered at the heel end by the heel band. No corresponding end-embracing member is, in the illustrated construction, employed at the toe end of the shoe, but in accordance with a feature of the invention two positioning means are employed which are connected operatively with the jacking means already described for positioning the toe end of the last during the jacking operation. Preferably the positioning means will be arranged to center the shoe upon the toe rest before the shoe is caused to bear with any considerable pressure upon the rest. As herein shown, the positioning means comprises engaging devices located on opposite sides of the shoe and normally standing away from the shoe to offer no obstruction to the lasting operation. These devices are carried by levers which are arranged to move together toward the shoe and are actuated by a yielding connection with a moving part of the jacking mechanism first toward the shoe to center it upon the toe rest and then away from the shoe. The yielding connection enables the devices to act satisfactorily upon shoes of different sizes. The engaging devices are arranged to contact with the sides of the shoe as near the toe end as may be without getting into the way of the toe-lasting plates. At this portion of the shoe the two side faces of the last are nearly the same distance from the median line of the fore part of the last and the shoe will, therefore, be positioned by them approximately centrally with relation to the machine. In very crooked lasts the outer side of the shoe is further than the inner side from the median line of the fore part, and I have, in accordance with a feature of this invention, made the engaging devices adjustable relatively on their carrying levers. As shown, these devices are blocks arranged to present different acting faces at different distances from their carrying levers and by suitably adjusting them lasts having different degrees of fullness can be correctly centered. 110 115

This invention also includes an improvement in the toe rest, which is arranged for sliding movement upon its support, against the tension of return springs both lengthwise and transversely of the last, and an improvement in the heel rest, which is mounted to tip laterally to adapt its position to variations in the position and inclination of the pin hole in the last. 120 125

The illustrated machine comprises, in accordance with another feature of the invention, means operating in connection with the 130

jacking mechanism to arrange and deliver tacks for securing the upper in its over-worked or lasted position. The tack arranging and delivering mechanism comprises, as shown, a hopper or reservoir to contain a mass of tacks and means for lifting tacks in small quantities and so manipulating or handling them as to cause them to become arranged in single line in an inclined raceway by which they are conducted to the tack-driving mechanism. This mechanism is operatively connected with the actuator for the jacking mechanism to be set into intermittent motion therewith.

15 It is found in practice that in order to provide a sufficient supply of tacks the supplying mechanism must continue to run through a considerable period and the best results are obtained by operating it slowly. 20 The preferred form of tack-supplying mechanism includes a rotary tack-lifting device for taking tacks from the mass and depositing them upon an arranging table leading to the raceway. It is found in practice 25 that the lifting device cannot advantageously be operated above a certain speed and that it is necessary to continue its actuation at such desirable speed through a longer period than that required for imparting to 30 the jacking mechanism its movements for positioning and clamping the shoe.

A feature of this invention, consists therefore, in interposing between tack-supplying mechanism and the actuator, which is common to it and to one of the mechanisms for operating on the shoe, herein shown as the jacking mechanism, suitable connections which will cause the tack-supplying mechanism to run after the other mechanism has 35 come to rest. Preferably these connections will be constructed and arranged to govern the speed at which the supplying mechanism is operated and as herein shown these connections include a spring arranged to be 40 put under tension by the movement of the actuator and a dash pot operating in a liquid, such as oil, for controlling the rate at 45 which the spring may react and actuate the supplying mechanism.

50 In the illustrated embodiment of the invention the wiper plates of one of the end-lasting mechanisms are connected, as has been stated, with the actuator which operates the jacking mechanism and which also 55 operates the tack-supplying mechanism, as has just been explained. By this connection the wiper plates are advanced toward the shoe when the tack-supplying mechanism is started and may afterward be further operated by their independent hand lever 60 while the supplying mechanism continues to run. The fastenings for securing the upper are herein referred to as tacks but other forms of fastenings might be used and the 65 supplying mechanism therefor connected to

a mechanism for operating on the shoe in accordance with this feature of the invention.

These and other features of the invention, including certain details of construction and combinations of parts, will be further explained in the following description and pointed out in the claims.

The expression "crooked last" is sometimes used herein for convenience in referring to lasts in which the median line of the fore part is oblique to the median line of the heel part.

Figure 1 is a side elevation of a lasting machine embodying this invention. Fig. 2 is a plan view of the machine showing a shoe for a right foot in the position occupied by it during the lasting operation. Fig. 3 is a similar view showing the shoe for the left foot in the position occupied by it during the lasting operation. Fig. 4 is a longitudinal vertical section of the machine. Fig. 5 is a detail showing provision for adjusting the center about which the heel-lasting mechanism turns. Fig. 6 is a section on the line 6-6 of Fig. 4. Fig. 7 is a transverse vertical section of the machine specially arranged to show the cams concerned in the jacking and unjacking operations and to show the mechanism for positioning the fore part of the shoe. Fig. 8 is a detail of the shoe positioning devices. Fig. 9 is an end view of the tack-supplying mechanism. Fig. 10 is a detail of parts shown in Fig. 9. Fig. 11 is a perspective view of parts shown in Fig. 9. Fig. 12 is a sectional view on line 12-12 of Fig. 3. Fig. 13 is a detail view of the locking devices for the heel-lasting mechanism as seen from the rear of the machine in Figs. 2 and 3. Fig. 14 is a vertical section through the locking pawl for the hand wheel and the device by which the pawl is tripped.

The frame 2 of the machine supports the toe-lasting mechanism A and the heel-lasting mechanism B between which are located the toe rest 4 and the heel rest 6. The heel-lasting mechanism is carried by a plate 3 which is connected pivotally with the frame by a pin 5. This pivot pin is located under the last and at a point removed from both ends of the last and at, or approximately at, the point of intersection of the median lines of the heel part and fore part of the last. If desired, the pin 5 may be adjustable—as, for example, by providing a slot in the frame, as shown in Fig. 5. By this means the center about which the heel-lasting mechanism is movable may be differently positioned for lasts in which the point of intersection of the median lines is located farther forward or backward in the last. In the movement of the heel-lasting mechanism about the pin 5 the plate 3 slides freely over the frame being supported by rolls as 125

shown in Figs. 1, 2 and 3 which travel on a curved track and the movement is limited by stops 7, shown in Figs. 2 and 3. These stops are adjustably mounted upon a right 5 and left threaded screw 9 equidistant from the middle line of the machine. The screw is provided with a crank by which it may be turned for adjusting the two stops together toward or from the middle of the 10 shoe. These stops serve to limit the lateral movement of the heel-lasting mechanism and when they have been adjusted into the right position for a right last, for example, they will be correctly located also for the left 15 last and for all lasts of the same style. The heel-lasting mechanism is provided with a locking device adapted to coöperate with either of the stops 7. This device comprises a movable block 11 having two hooks or 20 latches, as shown in Fig. 13 and operated through connections with the lever 13 for the purpose of unhooking it. The lever 13 is pivoted to a post 17 which is secured to the plate 3 of the heel-lasting mechanism so 25 that the operator may grasp the lever and the post and by a single movement unfasten the latch block from the stop and then move the heel-lasting mechanism laterally about the pivot 5.

30 The toe-lasting mechanism is carried by a bed plate 21, formed on the upper end of the vertically movable block 23, which is connected by a rod 27 with a crank 29 rigidly connected with the double-ended 35 treadle 31 by which the bed plate may be moved upwardly or downwardly. A screw 33 provided with a hand wheel is secured to the frame 37 of the toe-lasting mechanism and has screw-threaded engagement 40 with a stationary block 39 on the bed plate for moving the toe-lasting mechanism forwardly and backwardly to position it for lasts of different lengths, the toe rest being moved lengthwise of the shoe with the toe-lasting mechanism through its support 28, see Fig. 4. The carriage 41 is herein shown as pivotally connected at 43, see Figs. 1 and 3, with the frame 37 and arranged for 45 lateral movement about its center by means of the screw 47 provided with a hand wheel, as shown in Fig. 12. The toe-lasting devices are supported on a head which is pivoted at 51 to a carriage 41 and may be adjusted vertically about said pivot by the 50 screw 53, having the hand wheel 55, as shown in Fig. 12. The lasting devices are carried by a sleeve 57, to which is secured a segment 59 engaged by a screw 61 having a handle 63. By this latter means the toe-lasting devices may be tipped laterally to 55 adapt them to the lateral inclination of the bottom of the shoe. The heel-lasting mechanism is preferably arranged for similar tipping movement of the wiper plates by means of devices connected with the handle 63.

The toe-lasting devices comprise the wiper plates 67 removably attached to the carriers 69 and arranged for movement rearwardly and inwardly over the bottom of the toe portion of the last. This movement is effected by connections including the links 71 and equalizing lever 73 with an endwise movable rod 77 to which is connected the hand lever 79.

In bearings in the frame 2 there is mounted the cam shaft 8 to which is fixed a ratchet wheel 10 engaged by a pawl 12 mounted on a circularly movable pawl carrier 14 and connected by a rod 15 with a treadle 16, shown in Fig. 1. Any other convenient 75 means may be employed for intermittently actuating the cam shaft either manually or by power. Mounted upon the shaft is a cam 20, shown in Figs. 4 and 7, which engages a roll on a vertically movable slide 22, 80 guided in the frame and forming a movable support for the toe rest. This rest includes a rod 24 provided with an adjustable screw 26 at its lower end and contacting directly with the slide 22. The rod extends through 85 a guide 28 and is grooved to receive a screw which holds it from turning. The rod is provided with a head in which a slide 30 is movable transversely of the machine against the pressure of a spring 32, shown in dotted 90 lines in Fig. 4. A second slide 34, movable lengthwise of the machine and carrying the pad 4, is mounted in the slide 30 and is normally held in a central position by the spring 36, also shown in dotted lines. By 100 this arrangement of the toe rest and its actuating mechanism the toe pad may move freely either lengthwise or transversely of the machine with the last and is raised for lifting the last in the jacking operation.

105 The heel-lasting mechanism, together with the heel support, is movable lengthwise of the plate 3 from a retracted position which permits of the convenient insertion of the last to a predetermined operative position which is maintained during the jacking and lasting operations by the hook 35, carried by the heel lasting head and shown best in Fig. 1, which engages a projection on the side rail of the plate. This 110 hook is mounted on a rock shaft 81 carrying at the opposite side of the machine an arm 83 which rests upon a vertically movable rod 87, see Fig. 4, that is operated from a cam 89 on the cam shaft 8 to release the hook. This takes place as a part of the unjacking operation after the shoe has been lasted and occurs simultaneously with the opening of the heel band and the depression of the toe support. The heel rest is carried 115 by a slide 40, see Fig. 4, which is movable lengthwise of the machine in the plate 3 which supports the heel lasting mechanism and is therefore movable laterally about the pivot 5 with the heel-lasting mechanism.

For this purpose the slide is provided on its upper face with rack teeth, which are engaged by a pinion 42 on a shaft 44 having a hand wheel 45. The hand wheel is provided on its inner face with ratchet teeth which are engaged by a spring-pressed pawl 46, as shown in Figs. 2 and 3, to hold the parts in their adjusted position. A spring 48 acting against the slide presses the heel 10 rest forwardly away from the heel-lasting mechanism when the pawl 46 is released from the hand wheel. The release of the pawl from the teeth on the hand wheel may be effected manually at any time by means 15 of the lever 49 which extends upwardly from the pawl into convenient position to be engaged by the operator. Provision is also made in the cam 175, shown in Figs. 1, 2, and 3, for automatically disengaging 20 the pawl from the hand wheel and releasing the jack post during the return of the carriage from its lasting position. The cam 175 is fixed upon the plate 3 in position to engage by means of its inclined inner face 25 with a lug X depending from the pawl 46. The relation of the parts when the pawl is held out of engagement with the hand wheel by the cam 175 is shown in Fig. 14. A suitable spring, shown at x x, may be provided for pressing the pawl toward the 30 hand wheel into position to engage the teeth when the pawl is moved away from the cam 175. The heel post is provided in its lower end with an adjusting screw 50 which rests 35 upon a plate 52 connected pivotally to the slide 40 at 54 and having an inclined face which rests upon the end of a screw 55. This screw is freely movable endwise in the carriage of the heel-lasting mechanism and 40 is adjustable in a nut 56, which is supported by a spring 58. The screw thus provides a yielding support for the plate 52 and by its engagement with the inclined face of the plate causes the plate to be lifted as the slide 45 40 and heel post are moved rearwardly, to draw the last into the heel band of the heel-lasting mechanism. This arrangement provides for adjusting the heel post vertically according to the size of the last inasmuch as 50 the extent of the backward movement of the post into the band will vary according to the distance between the pin hole and the rear end of the last, being less for a large last than for a small one. This engagement 55 of the shoe with the band causes the post to rock or fulcrum about the upper portion of its guide in the slide 40 so that the lower portion of the post, which is toothed as shown in Fig. 4, is forced into engagement 60 with some pawls, the guideway in the slide being somewhat larger at its lower portion than is the post so that this movement of the post is permitted.

The teeth are formed to hold the post 35 against downward movement, but offer no

obstacle to the upward movement of the post. When the post is tipped out of contact with the pawls it is free to move either upwardly or downwardly. A rod 60 is arranged below the plate 52 and connected to a treadle 62, shown in Fig. 1, for raising the heel post and the heel end of the shoe or positively upholding them during the lasting operation if desired. The heel post is reduced somewhat in width at its upper end, as shown in the sectional view Fig. 6 to permit the post to move sidewise slightly. Springs 64 hold the post normally in its central position. The heel pin 65, which enters the pin hole of the last, is tapered to permit some movement of the last thereon and is connected to the post by a ball and socket joint. This provision for the post to move laterally and the pin to move independently upon the post enables the heel support to adapt its position to the position and the inclination of the pin hole in the last. This is an advantage because the pin holes in lasts are not always accurately located, or drilled at the same inclination to the face of the last, and, moreover, in some very crooked lasts the pin hole is located on the right side of the median line of the heel part of a right last and on the left side of this median line of a left last. The jacking operation effected by the machine is produced by depressing the foot treadle 16 after the last with the upper materials assembled on it has been placed upon the heel and toe rests and the heel rest has been moved backwardly by the hand wheel 45 to draw the shoe into the heel band and lock the post against vertical displacement all as above described. This actuation of the treadle turns the cam shaft and causes the cam 20 to raise the toe rest positively as previously explained, thus forcing the last firmly back into the heel band and clamping it rigidly in position to be lasted. The cam shaft also carries a cam 70 which actuates during this jacking operation devices connected with the heel band for closing the band about the sides of the heel portion of the last to force the upper materials, including the heel stiffener, snugly into contact with the sides of the last. This cam 70, as shown best in Figs. 4 and 7, engages a roll on the lever 72, which is connected by a bar 74 with a lever 75. The bar 74 is formed in two parts, as shown in Fig. 4, to permit of the described lateral movement of the heel-lasting mechanism. The lower rear end of the lever 75 engages a lever 76 fulcrumed at 78 in the carriage of the heel-lasting mechanism. This lever is connected by a spring 80 with a block 82, see Figs. 1, 3, and 4. This block is securely clamped to a slide rod 84 and forms the head of this rod, which, as indicated in Fig. 2, extends lengthwise through the head of the heel-lasting mecha-

nism and is pivotally connected to an evener or equalizing bar 85, shown in dotted lines in Fig. 2. This bar is provided at its two ends with links 86 to which are pivoted levers 88. The outer ends of these levers are connected to springs 90, while their inner ends are connected to the front ends of the heel band. This arrangement is such that as the cam 70 is actuated during the jacking operation the rod 84 will be moved forwardly and cause the levers 88 to be advanced and rocked for drawing the heel band forwardly and forcing its end portions inwardly against the sides of the shoe, whereby the shoe is clamped laterally in the heel-lasting mechanism by the jacking operation. During this operation the spring 80 is put under tension and the power thereby stored is subsequently utilized when the spring contracts to automatically move the heel lasting mechanism rearwardly, and to open the heel band to release the shoe from clamping engagement therewith. The heel-lasting mechanism includes the wiper plates 100 which are mounted on plate carriers guided for sliding movements in the carriage of the heel-lasting mechanism, and connected by the rods 102, the equalizing lever 104, and a slide rod 105 with a lever 106. The lever 106 is fulcrumed on a link 108 attached to a fixed part of the mechanism and is adapted to be actuated manually for advancing and closing the wiper plates over the shoe bottom at the heel end of the last. The block 82, above mentioned as being actuated lengthwise of the machine during the jacking operation for closing the heel band, is extended vertically and connected to a rod 110 which is provided at its forward end with links 112 having pin and slot connections with the wiper plate carriers. This arrangement provides that during the jacking operation when the block 82 is advanced for closing the heel clamps the wiper plates will also be advanced and closed. The arrangement is such that when the wiper plates are retracted and opened prior to removing a shoe from the machine the pins of the pin and slot connection stand against the rear ends of the slots in the rods 112 so that during the jacking operation of the next shoe the forward movement of the block 82 will cause the links to thrust the plates forwardly. The momentum of the plates carries them forwardly until they engage the upper at or adjacent to the edge of the heel of the shoe. By this means the wiper plates are initially positioned during the jacking operation close to or slightly over the edge of the last in position for the workman to manipulate them for forcing the upper into lasted position on the shoe bottom. One advantage of this arrangement is that the handle end of the long lever 106, which has a considerable range of movement, is auto-

matically brought up into position to be conveniently engaged by the workman. The cam shaft 8 carries, in addition to the parts before mentioned, a disk having a projection 120, shown best in Fig. 7, which engages a roll on an angle lever 122, to the upper end of which is connected a yielding plunger 124 pivoted to a swinging arm 125, as shown in said Fig. 7. The arm 125 is connected by three links, the middle one of which is pivoted to the fixed bracket 135, with a similar arm 126 mounted on the opposite side of the machine and arranged to be moved by the links with the arm 125 toward and from the last. The arms are provided with devices for engaging the sides of the shoe for positioning it upon the toe rest in the middle of the machine, or in correct operative relation to the toe-lasting devices. This centering of the toe end of the shoe forms a part of the jacking operation and the cam 120 is, therefore, located on the cam shaft with relation to the other cams to cause the positioning devices carried by the arms to center the shoe before the shoe is clamped by the heel band. The positioning devices carried by the arms are herein shown as blocks 128 adapted to fit upon pins projecting from the arms. Each block is provided with a pin hole so located with relation to the sides of the block that the side faces are each a different distance from the pin. A locking device 130 is arranged to hold the block in its adjusted position. A spring 132 extends from one of the links to an adjusting screw 134 in the stand 135 for holding the positioning devices normally away from the shoe. The cam projection 120 is so formed that the spring may move the positioning devices away from the shoe immediately after the shoe has been centered upon the toe rest. The treadle 16, by which the cam shaft is turned for actuating the several jacking means is connected by the link 140 with a rack bar 142, which engages a pinion 144. The pinion is mounted on a shaft to which is connected, as shown in Fig. 9, a flanged disk 145. A strong coiled spring 146 is connected at one end to the flange of the disk 145 and at the other end to a fixed portion of the frame at 148 so that the spring is wound up and put under tension when the treadle is depressed for actuating the jacking mechanism. The rack bar 142 is connected to a piston 150 operating in a cylinder 152 having a channel communicating with a receptacle 154 adapted to contain a liquid, such as oil. A screw 155 is arranged to be adjusted for varying the size of the channel. By this dash pot arrangement the spring 146 is compelled to unwind slowly and at a rate which can be regulated. The flanged disk 145 carries a pawl 156 which is in engagement with a ratchet 158 on a pulley 160. A belt 162 extends from this pulley 160.

ley to a pulley on the shaft of the rotatable tack hopper 164. The hopper has shelves 163 by which tacks are lifted and deposited upon a receiving plate 165 and fall into a trough 166 leading to a raceway 168 by which they are delivered to a removable hand tacking tool 170.

The table 165 is pivotally supported at its rear edge and rests at its front end upon a lever 172, the lower end of which extends under the tacker 170 when the tacker is in position to receive tacks. When the tacker is removed the weight of the table causes it to tilt downwardly and throw off the tacks which have accumulated upon it instead of falling into the trough and raceway. When the tacker is returned to tack receiving position the lever 172 is rocked in the direction to restore the table to its normal position.

In the use of the machine the workman selects the shoe to be lasted and according as the shoe is for a right or a left foot, he usually shifts the heel-lasting mechanism laterally about the pivot 5. He then places the shoe upon the heel rest and runs the heel-lasting mechanism forwardly into its operative position where it is held by the hook 35. The forward portion of the last 30 rests at this time upon the toe support and its end should be centered between the toe wipers. The angular position of the shoe in the machine is then observed and if it is not such that the toe faces squarely toward the toe-lasting mechanism with the median line of the forepart of the last coinciding with the median line of the machine, and that the heel-lasting mechanism is symmetrical with relation to the median line of the heel portion of the last, then the lateral angular adjustment of the shoe and the heel lasting mechanism is corrected to obtain these relative positions. In altering the adjustment the heel post will be carried 45 toward one side of the machine until the median line of the forepart of the last, which intersects the median line of the machine substantially at the tip of the toe, coincides with the median line of the machine 50 throughout the length of the forepart of the shoe. This movement of the last is an angular adjustment laterally about a center at or near the toe, the toe end of the last being more or less confined between the toe 55 wipers and sustained on the laterally movable toe rest. The adjustment of the heel-lasting mechanism takes place at the same time with the adjustment of the last and through the same distance as that of the heel 60 end of the last but its center of movement is at the intersection, at pivot 5, of the median line of the heel part of the last with that of the toe part and, because it has the shorter radius of movement said heel lasting mechanism turns through a larger angle

than does the last and therefore receives an angular adjustment relatively to the last. This differential adjustment is enough to set the heel-lasting mechanism into symmetrical relation to the median line of the heel portion of the last. Then by means of the hand wheel 45 the heel post is moved rearwardly and upwardly for drawing the heel portion of the last firmly into the rear portion of the heel band and to raise the last to present the bottom face of the shoe in the plane of the heel wiper plates. The operator then depresses the treadle 16 for causing the jacking mechanism and the tack-supplying mechanism to be operated. By this movement of the treadle the spring 146 of the tack-supplying mechanism is wound up and during the jacking operation and subsequent operations connected with the lasting of the shoe the spring unwinds, at a rate determined by the adjustment of the dash pot arrangement, for causing tacks to be arranged and delivered to the tacker 170.

The movement of the cam shaft produced by the depression of the treadle is communicated through the cam projection 120 to actuate the shoe-centering devices for positioning the shoe upon the toe rest. The toe rest is then lifted to tip the shoe backwardly toward and into the heel band and the heel band is closed through motion communicated from the cam 70 to clamp the sides of the last. The movement communicated from the cam 70 also is transmitted through the block 82 and rod 110 to the heel wiper plates for advancing those plates up to or slightly over the edge of the last and move the hand lever 106 into position to be conveniently grasped by the operator. These jacking operations having been completed, the workman, by means of the hand levers 79 and 106, works the upper over the toe and heel ends of the last into position to be secured.

Usually the foot treadle 62 is employed for raising the last upwardly against the heel plate to compact the overworked upper material against the innersole before it is fastened and the workman also usually employs the double-ended treadle 31 for moving the toe-lasting devices upwardly and downwardly to cause them first to wipe the shoe stock upwardly toward the edge of the last and after the wipers have moved over the last, the head is depressed for causing the wipers to compact the stock on the innersole. The tacking tool 170 is then removed from the raceway and used for inserting tacks to secure the upper at the heel portion of the last and sometimes at the toe portion. In lasting welt shoes it is, however, customary to fasten the upper at the toe portion of the shoe with a binder of continuous material instead of using tacks for the pur-

pose. When the lasting has been completed the cam shaft is again actuated by the treadle 16 and the cams turned into a position to unlock the hook 35, thus permitting the heel-lasting mechanism to move rearwardly by the contraction of the spring 80 which reacts through the lever 76 against the arm of the lever 75, causing the heel band to open for unclamping the shoe. As the heel-lasting mechanism retreats the pawl 46 contacts with the tripping device 175 and is freed from the ratchet on the hand-wheel 45, thus permitting the spring 48 to force the heel support and the shoe out of the heel band. The toe rest is also lowered into its shoe-receiving position, after which the workman removes the lasted shoe from the heel and toe supports. In proceeding to last another shoe if it is a shoe for the same foot as the one last operated upon and is the same style of last, no lateral adjustment of the heel-lasting mechanism will be required. If the last is of a somewhat different style, being more or less crooked, a slight lateral adjustment of the heel-lasting mechanism will position it with relation to the toe-lasting mechanism. When a shoe for the other foot is to be lasted the operator frees the locking block 11 of the heel-lasting mechanism from the stop 7 by manipulating the lever 13 and by movement applied to the post 17 shifts the heel-lasting mechanism to the opposite side of the machine until it engages with the stop 7 at that side where it will be locked by the block 11. The heel-lasting mechanism will then be properly positioned with relation to the toe-lasting mechanism for these mechanisms to operate upon the right shoe of a pair of shoes, supposing that the last shoe was for the left foot. If at any time after a shoe has been jacked it is found that the toe portion of the shoe is not presented accurately to the toe wiper plates or that because of an irregularity in the formation of the channel lip the upper requires to be forced over the last bottom farther on one side of the shoe than on the other side the toe-lasting mechanism can be moved laterally about the pivot 43 for positioning it properly with relation to the particular shoe in the machine. The operator will, of course, also adjust the toe and heel-lasting mechanisms by means of the adjusting devices 55 and 63, according to the variations in the inclinations of the bottom faces of the different lasts as conditions may require.

The present application is a continuation of the application for Letters Patent of the United States, Serial No. 666,143, filed January 10, 1898, so far as said applications disclose common subject-matter.

The invention herein disclosed in the shoe supporting mechanism is not claimed in this application, but forms the subject-matter of

a divisional application Serial No. 557,880, filed April 27, 1910.

Having explained the nature of this invention and described a preferred construction embodying the invention, I claim as new and desire to secure by Letters Patent of the United States:

1. A machine for use in lasting shoes and boots comprising lasting devices for acting upon opposite ends of the last constructed and arranged for relative movement about a center approximately at the intersection of the median line of the heel part and the median line of the fore part of the last. 75
2. In a lasting machine, a stationary end-lasting mechanism having its median line in the median line of the machine, and an opposed end-lasting mechanism movable laterally about a center located at or near the point of intersection of the median lines of the fore part and the heel part of the shoe upon which said mechanisms are to operate. 85
3. In a machine for use in lasting shoes the combination with means for supporting the last, of end-lasting mechanism arranged for relative lateral movement about a center approximately at the intersection of the median lines of the heel part and the fore part of the last. 90
4. In a machine for use in lasting shoes the combination with toe-lasting mechanism, of a heel support and a heel-lasting mechanism movable about a center approximately at the intersection of the median lines of the heel part and the fore part of the last. 100
5. In a machine for use in lasting shoes the combination with toe-lasting mechanism, of a support for the heel portion of the last movable laterally about a center approximately at the intersection of the median lines of the heel part and the fore part of the last. 105
6. In a machine for use in lasting shoes the combination with a toe-lasting mechanism, of a heel support and a heel-lasting mechanism operatively connected for movement together about a center located approximately at the intersection of the median lines of the heel part and the fore part of the last. 110
7. In a machine for use in lasting shoes the combination with end-lasting mechanism, lasting devices adapted for the other end of the last and operating means therefor, a carriage upon which said devices and operating means are mounted and which is constructed and arranged for movement about a center located approximately at the intersection of the median lines of the heel part and the fore part of the last. 125
8. A machine for use in lasting shoes and boots comprising lasting devices for acting upon opposite ends of the last constructed and arranged for relative movement angularly about an axis which is substantially 130

- perpendicular to the plane of the shoe bottom and is located under the last and at a substantial distance from either end of the last.
5. 9. In a machine for use in lasting shoes the combination with means for supporting the last, of end-lasting mechanism for each end of the last constructed and arranged for relative lateral movement about an axis 70
- 10 which is substantially perpendicular to the plane of the shoe bottom and is located under the last and at a substantial distance from either end of the last.
10. In a machine for use in lasting shoes 15 the combination with end-lasting mechanism for one end of the last, of lasting devices adapted for the other end of the last and operating means therefor, a carriage upon which said devices and operating
- 20 means are mounted and which is constructed and arranged for movement relatively to said end lasting mechanism about a center located under the last and at a substantial distance from either end of the last.
- 25 11. In a machine of the class described, the combination with means for positioning the fore part of a last, of mechanism for acting upon the rear part of the last constructed and arranged to permit of lateral 80
- 30 adjustment about a center located approximately at the intersection of the median lines of the fore part and the heel part of the last. 85
12. In a machine of the class described, 35 the combination with means for positioning the fore part of a last, of mechanism for acting upon the rear part of the last constructed and arranged to permit of lateral adjustment about a center located at such 90
- 40 a point between and removed from the ends of the last that said mechanism may be positioned to act uniformly upon a right or a left crooked last.
13. In a machine for use in lasting shoes, 45 end-lasting mechanism constructed and arranged for relative movement laterally about a center located approximately at the intersection of the median lines of the heel 100
- 50 part and the fore part of the last, said mechanism having provision for movement of one of said end-lasting mechanisms about a different center for supplemental adjustment. 105
14. In a machine for use in lasting shoes, 55 end-lasting mechanisms constructed and arranged for relative movement laterally about a center located approximately at the intersection of the median lines of the heel 110
- 60 part and the fore part of the last, combined with means for adjusting one of said end-lasting mechanisms about a different center. 115
15. In a machine for use in lasting shoes, an end-lasting mechanism constructed and arranged for adjustment laterally about a 120
- 65 center located under the last and substan- tially removed from both ends of the last, a second end-lasting mechanism, and means for adjusting it laterally. 125
16. In a mechanism for use in lasting shoes, a heel-lasting mechanism constructed 70 and arranged for lateral adjustment about a center located under the last and substantially removed from both ends of the last, a toe-lasting mechanism, and means for moving the toe lasting mechanism laterally 75
- about a different center.
17. In a machine for lasting shoes, heel-lasting mechanism constructed and arranged for lateral adjustment before the shoe is jacked about a center located approximately 80
- at the intersection of the median lines of the heel part and fore part of the last, a toe-lasting mechanism, and means constructed and arranged for adjusting the toe-lasting mechanism laterally after the shoe is jacked. 85
18. In a machine for lasting shoes, a heel-lasting mechanism movable laterally about a center located under the last and removed from both ends of the last to adapt it for use with right and left lasts, means for jacking the last having provision for causing the heel-lasting mechanism to clamp the last, and a toe-lasting mechanism constructed and arranged for lateral adjustment after the shoe has been jacked. 90
19. In a machine for use in lasting shoes, a toe-lasting mechanism, a shoe support constructed and arranged for movement laterally about a center located under the last and removed from both ends of the last to 100
- adapt it to support right and left lasts in substantially the same relation to the toe-lasting mechanism, means for jacking the shoe, and means by which the toe-lasting mechanism may be adjusted laterally after the shoe has been jacked. 105
20. In a machine for use in lasting shoes, a toe-lasting mechanism, a shoe heel support constructed and arranged for movement laterally about a center located under the last and removed from both ends of the last to 110
- adapt it to support right and left lasts in substantially the same relation to the toe-lasting mechanism, a toe support restrained from lateral movement with the heel support, and means for adjusting the toe-lasting mechanism laterally. 115
21. In a machine of the class described, the combination with means for positioning the fore part of a last, of mechanism for acting upon the rear part of the last constructed and arranged to permit of lateral adjustment about a center located approximately at the intersection of the median line 120
- of the fore part and the heel part of the last, and adjustable means for limiting the movement of said mechanism equally toward the opposite sides of the machine. 125
22. In a machine of the class described, the combination with means for positioning 130

- the fore part of a last, of mechanism for acting upon the rear part of the last constructed and arranged to permit of lateral adjustment about a center located approximately at the intersection of the median line of the fore part and the heel part of the last, stops for limiting the movement of said mechanism toward the opposite sides of the machine, and means for adjusting the stops together toward and from the middle of the machine. 5
23. In a machine of the class described, the combination with means for positioning the fore part of a last, of mechanism for acting upon the rear part of the last constructed and arranged to permit of lateral adjustment about a center located approximately at the intersection of the median line of the fore part and the heel part of the last, stops for limiting the movement of said mechanism toward the opposite sides of the machine, means for adjusting the stops together toward and from the middle of the machine, and means coöperating with the stops for locking the mechanism in its laterally adjusted position. 15
24. In a machine of the class described, the combination with means for positioning the fore part of a last, of mechanism for acting upon the rear part of the last constructed and arranged to permit lateral movement about a center located under the last, means for limiting the lateral movement in either direction, and means for adjusting the limiting means together in opposite directions. 20
25. In a machine of the class described, the combination with means for positioning the fore part of a last, of mechanism for acting upon the rear part of the last constructed and arranged to permit lateral movement about a center located under the last, means for limiting the lateral movement in either direction, and means carried by the mechanism and coöperating with the limiting means to lock the mechanism in either extreme of its movement. 25
26. In a lasting machine, the combination with a movable heel lasting carriage, of a jack post, means including the toothed hand wheel 45 for retracting the jack post relatively to the carriage, a pawl 46 for locking the hand wheel, and a cam 175 for withdrawing the pawl from the hand wheel for releasing the jack post. 30
27. In a lasting machine, the combination with heel lasting mechanism, of a movable support therefor, a jack post, means for retracting said jack post relatively to said support, retaining means for retaining said post in its retracted position, and means stationary relatively to said carriage for withdrawing said retaining devices from engagement with the said retracting means. 35
28. A lasting machine, comprising end-lasting mechanisms mounted to have a relative bodily angular movement laterally into positions for acting uniformly upon the opposite ends of right and left crooked lasts, and having provision for maintaining said mechanisms against lateral displacement during the lasting operation. 40
29. A lasting machine, comprising a heel-lasting mechanism including a heel-embracing band and movable laterally about a center located under and removed from the ends of the last into different positions to cause the band to act uniformly upon the two sides of the heel of a right or a left shoe, said machine having provision for maintaining the heel-lasting mechanism in its laterally adjusted position during the operation of the band. 45
30. A lasting machine, comprising heel and toe-lasting mechanisms relatively movable laterally into positions for acting upon right and left lasts and having provision for maintaining the heel-lasting mechanism against lateral displacement during the lasting operation, combined with additional means arranged to be actuated manually for shifting the toe lasting mechanism laterally. 50
31. A lasting machine, comprising a heel-lasting mechanism movable laterally into positions for acting upon right and left lasts and having provision for maintaining said mechanism against lateral displacement during the lasting operation, combined with a toe-lasting mechanism including wiper plates and means arranged to be actuated for shifting the wiper plates laterally while they are in operative engagement with the shoe. 55
32. In an end-lasting mechanism, the combination with an end-embracing band and wiper plates, of means for automatically actuating the band to clamp the upper materials to the side of the last, said means being constructed and arranged to cause the wiper plates to be advanced when the band is closed. 60
33. In an end-lasting mechanism, the combination with an end-embracing band and wiper plates, of means for actuating the band to clamp the upper materials to the side of the last, said means being constructed and arranged to cause the wiper plates to be advanced when the band is closed from a retracted position into a position to be subsequently actuated for wiping the upper over the last bottom, and means for independently actuating the wiper plates for the purpose described. 65
34. In an end-lasting mechanism, the combination with an end-embracing band and wiper plates, of means for actuating the band to clamp the upper materials to the side of the last, and operative connections between the plates and the band-actuating means constructed and arranged to cause 70
- 75
- 80

the plates to be positioned at the edge of the last when the band is closed.

35. In a machine of the class described, the combination with a heel band, lasting plates, and shoe jacking mechanism including means for lifting the shoe to the level of the plates and closing the band, of connections through which the plates are automatically advanced during the operation of the jacking mechanism.

36. In a lasting machine, the combination with a last support and wiper plates, of means for lifting the last to present the shoe bottom at an appropriate level with relation to the plates, and means for automatically advancing the wiper plates longitudinally of and into a position adjacent to the edge of the last when the last is raised.

37. In a lasting machine, the combination with a last support and wiper plates, of connected devices for raising the shoe and advancing the wiper plates in a direction at right angles to the lifting movement to a position adjacent to the edge of the last.

25 38. A lasting machine having lasting plates and having provision for automatically moving the plates longitudinally from a retracted position into a position adjacent to the edge of the last, and means for manually actuating the plates over the edge of the last.

39. In a machine of the class described, the combination with end-lasting mechanism, of means that are actuated into and 35 out of engagement with the shoe and operating while the shoe is being jacked to center the toe portion of the shoe with relation to the end-lasting mechanism.

40. In a machine of the class described, 40 the combination with end-lasting mechanism, of means operating automatically while the shoe is being jacked to center the shoe and then disengage the shoe.

41. In a machine of the class described, 45 the combination with end-lasting mechanism and a rest for the shoe, of devices for engaging opposite sides of the shoe, and means for yieldingly actuating said devices toward the shoe to center it on the rest and 50 then move the engaging devices away from the shoe.

42. In a machine of the class described, the combination with end-lasting mechanism, of means for centering the shoe, comprising relatively adjustable engaging devices, and means for actuating the devices toward and from the shoe.

43. In a machine of the class described, 60 the combination with end-lasting mechanism, of means for centering the shoe, comprising eccentrically mounted contact blocks, supports on which the blocks are adjustably mounted, and means for actuating the supports toward and from the shoe.

35 44. In a shoe centering mechanism, a

block and a support, said block having a plurality of contact faces located at different distances from the point of connection of the block with the support, combined with connecting means between the block and support constructed and arranged to maintain the block with any one of its contact faces in operative relation to the work.

45. In a machine for working an upper over a last into position to be fastened by tacks, mechanism for jacking the shoe, combined with mechanism operatively connected with the jacking mechanism to arrange and deliver the fastening tacks.

46. In a machine for working an upper over a last into position to be fastened by tacks, mechanism for jacking the shoe, and mechanism for arranging and delivering the fastening tacks, combined with actuating means operatively connected with the jacking mechanism and the tack-supplying mechanism, whereby said two mechanisms are set into operation simultaneously.

47. In a machine for working an upper over a last into position to be fastened by tacks, mechanism for jacking the shoe, and mechanism for arranging and delivering the fastening tacks, combined with means to actuate the jacking mechanism to position and clamp the shoe and to set into operation a slow moving actuator for the tack-supplying mechanism.

48. In a machine for working an upper over a last into position to be fastened by tacks, mechanism for jacking the shoe, and mechanism for arranging and delivering the fastening tacks, combined with means to actuate the jacking mechanism to position and clamp the shoe and a spring operatively connected with said actuating means and the tack-supplying means and arranged to communicate motion to the tack-supplying mechanism.

49. In a machine for working an upper over a last into position to be fastened by tacks, mechanism for jacking the shoe, and mechanism for arranging and delivering the fastening tacks, combined with means to actuate the jacking mechanism to position and clamp the shoe, a spring connected with the actuating means and with the tack-supplying mechanism, and a speed-controlling means whereby the tack-supplying mechanism may be operated at a different speed from the jacking mechanism.

50. In a machine for working an upper over a last into position to be fastened by tacks, mechanism for jacking the shoe, and mechanism for supplying tacks, combined with an actuator and connections between the actuator and said mechanisms constructed and arranged to actuate the two mechanisms at different relative speeds.

51. In a machine for working an upper over a last into position to be secured by

fastenings, heel wipers for operating on a shoe, combined with fastener-supplying mechanism, connected devices for advancing the heel wipers to the edge of the last and 5 for operating the fastener-supplying mechanism, and means for independently actuating the heel wipers.

52. In a machine for working an upper over a last into position to be fastened by 10 tacks, mechanism for jacking the shoe and mechanism for supplying tacks, combined with an actuator, connections between the actuator and the jacking mechanism to cause the latter to position and clamp the shoe and 15 then come to rest, and connections between the actuator and the tack-supplying mechanism to continue to actuate the latter after the jacking mechanism comes to rest.

53. In a machine for working an upper 20 over a last into position to be fastened by tacks, mechanism for jacking the shoe, and mechanism for supplying tacks, combined with an actuator, connections between the actuator and the jacking mechanism to cause 25 the latter to position and clamp the shoe and then come to rest, and connections between the actuator and the tack-supplying mechanism constructed and arranged to store up 30 energy during the movement of the actuator for operating the tack-supplying mechanism while the actuator is at rest.

54. In a machine for working an upper over a last into position to be fastened by 35 tacks, mechanism for jacking the shoe and mechanism for supplying tacks, combined with an actuator, connections between the actuator and the jacking mechanism to cause the latter to position and clamp the shoe and then come to rest, and connections between 40 the actuator and the tack-supplying mechanism constructed and arranged to store up energy during the movement of the actuator for operating the tack-supplying mechanism while the actuator is at rest, and means 45 independent of the actuator for controlling the speed at which the tack-supplying mechanism is operated.

55. In a machine for working an upper over a last into position to be fastened by 50 tacks, mechanism for jacking the shoe, and mechanism for supplying tacks, combined with an actuator, connections between the actuator and the jacking mechanism to cause the latter to position and clamp the shoe 55 and then come to rest, and connections between the actuator and the tack-supplying mechanism including a spring and a dash pot.

56. In a machine for working an upper 60 over a last into position to be fastened by tacks, the combination with an end-lasting mechanism comprising lasting plates, and a mechanism for supplying tacks to fasten the upper in lasted position, combined with

an actuator, connections between the actuator and the end-lasting mechanism to advance the lasting plates, and connections between the actuator and the tack-supplying mechanism to cause it to arrange and deliver tacks.

57. In a machine for working an upper over a last and fastening it, lasting mechanism and jacking mechanism for positioning and clamping a shoe in relation to the lasting mechanism, combined with mechanism operatively connected with the jacking mechanism to arrange and deliver the fastening tacks.

58. In a machine for use in lasting shoes comprising end-lasting devices arranged for 80 movement laterally with relation to the last about a center located approximately at the intersection of the median lines of the heel and toe portions of the last, said machine having provision for adjustment of the 85 center.

59. A lasting machine having a toe-lasting mechanism and a heel-lasting mechanism relatively movable about a center located approximately at the intersection of 90 the median lines of the heel and toe portions of the last, said machine being constructed and arranged to permit the said center of movement to be shifted.

60. A lasting machine having a toe-lasting mechanism and a heel-lasting mechanism movable laterally about a center located under the last and removed from both ends of the last, said machine being constructed and arranged to permit the said 100 center to be shifted lengthwise of the last.

61. A lasting machine having a toe-lasting mechanism, and a heel-lasting mechanism movable laterally about a center located under the last and removed from both 105 ends of the last, said machine being constructed and arranged to permit the said center to be shifted lengthwise of the last, combined with means for turning the toe lasting mechanism laterally.

62. In a lasting machine, a toe-lasting mechanism and a heel-lasting mechanism constructed and arranged for relative lateral movement about a center which is located under the last and can be shifted 115 lengthwise of the last.

63. The combination with end-lasting mechanism for one end of a last, of lasting devices adapted for the other end of the last, and actuating means for said devices 120 and mechanism said mechanism and devices with their actuating means being arranged for relative adjustment to cause them to advance symmetrically along the fore part and the heel part of the last with relation 125 to the median lines of said parts.

64. A machine for lasting boots and shoes comprising lasting devices for acting upon

opposite ends of the last arranged for relative adjustment to position said devices for lasting movements in the directions of the median lines of the fore part and the heel 5 part of the last irrespective of the angular relation of said median lines.

65. In a machine of the class described, the combination with means for positioning one end of a last, of lasting mechanism 10 for acting upon the opposite end of the last constructed and arranged for lateral adjustment relatively to said means to position said mechanism for advancing symmetrically over the end part of a right or a left 15 last in the direction of the median line thereof.

66. In a machine of the class described, the combination with means for positioning the fore part of a last, of lasting mechanism 20 for acting upon the rear part of the last constructed and arranged for adjustment to position for acting uniformly along the rear part of a right or a left last in the direction of the median line thereof.

67. In an end lasting mechanism, the combination with an end-embracing band, of means for actuating the band to clamp the upper materials to the sides of the last including a yielding member arranged to 30 be put under tension, said member being constructed and arranged to actuate the band reversely for unclamping the upper materials at the completion of the lasting operation.

68. In an end lasting mechanism, the combination with an end-embracing band, of means for actuating the band to clamp the upper materials to the sides of the last including a spring arranged to be put under 40 tension during the clamping operation, and means to permit said spring to react and thereby to actuate the band for unclamping the shoe at the completion of the lasting operation.

69. In an end lasting mechanism, the combination with an end-embracing band and wiper plates, of means for actuating the band to clamp the upper materials to the sides of the last and to advance the 50 wiper plates, including a spring arranged to be put under tension, and means arranged to cause said spring to react and to move the band and wiper plates rearwardly and unclamp the upper materials at the completion of the lasting operation.

70. A machine of the class described, having in combination, a toe lasting mechanism, a toe rest located to provide a support for the forepart of the shoe in the median line 60 of the machine, and a heel rest which is mounted for lateral movement about a center removed longitudinally of the machine a substantial distance from the toe rest.

71. A machine of the class described, hav-

ing in combination, overworking means for 65 the toe end of a shoe and shoe supporting mechanism comprising a forepart rest and an end abutment for the heel end face of the shoe which is mounted for bodily lateral curvilinear movement relative to the forepart rest to adapt its position to that of the heel ends of right and left crooked lasts which are presented with their foreparts in uniform relation to the overworking means. 70

72. A machine of the class described, having in combination, toe lasting mechanism, shoe supporting means comprising an end abutment for the heel end face of the shoe, said machine having provision for permitting lateral curvilinear bodily movement of 75 said abutment into position to support right and left crooked lasts, the foreparts of which are presented symmetrically to the toe lasting mechanism, and means for retaining said abutment in laterally adjusted 80 position.

73. A machine of the class described, having in combination, overworking means for the toe end of a shoe and shoe supporting mechanism comprising a forepart rest and 90 an abutment for the heel end face of the shoe which is constructed and arranged relatively to the fore part rest to support the heel ends of right and left crooked lasts at opposite sides of the median line of the machine while 95 the foreparts are supported symmetrically with relation to the median line of the machine by said forepart rest.

74. A machine of the class described, having in combination, toe lasting mechanism, 100 shoe supporting mechanism including a forepart rest and a heel rest which is movable laterally relative to the lasting mechanism and the forepart rest to support right and left shoes with their foreparts in similar relation to the lasting means, and adjustable means for limiting the lateral movement of the heel rest. 105

75. A machine of the class described, having in combination, toe lasting mechanism, 110 shoe supporting mechanism including a forepart rest and a heel rest which is movable laterally relative to the lasting mechanism to support right and left shoes with their foreparts in similar relation to the 115 lasting means, and stops adjustable together for limiting movement of the heel rest laterally toward either side of the machine.

76. A lasting machine, having in combination, lasting devices for acting on opposite 120 ends of a crooked last and which are supported for relative lateral curvilinear movement in a path having its approximate center located substantially at the intersection of the median lines of the forepart and the 125 heel part of the last.

77. A lasting machine, having in combination, lasting devices for acting on oppo-

- site ends of a last and which are constructed and arranged for relative lateral movement in a curvilinear path about an axis that is located under the last at a substantial distance from either end of the last, and a last support which is operatively connected with the laterally movable lasting mechanism and maintains a predetermined relationship therewith.
- 10 78. A lasting machine, having in combination, lasting devices for acting on opposite ends of a last and which are constructed and arranged for relative lateral movement about an axis which is located under the last and at a substantial distance from either end of the last, and means permitting relative adjustment of one lasting mechanism and said axis longitudinally of the machine.

- 20 79. A lasting machine, having in combination, lasting devices for acting on opposite ends of a last and which are constructed and arranged for relative lateral movement about an axis which is located under the last and at a substantial distance from either end of the last, and means to lock the laterally movable lasting device in the positions to which it is adjusted.

- 30 80. A machine of the class described; having in combination, lasting devices for acting on opposite ends of a last and which are constructed and arranged for relative lateral movement about an axis which is located under the last and at a substantial distance from either end of the last to adapt them for operating upon right and left crooked lasts, and means permitting adjustment of one of said mechanisms about a different axis which is substantially parallel with the first mentioned axis.

- 40 81. In an end lasting mechanism the combination with an end embracing band and wiper plates; of means for actuating the band to clamp the upper materials to the sides of the last; said means being constructed and arranged to cause the wiper plates to be advanced, when the band is closed from a retracted position, into a position to be subsequently actuated for wiping the upper over the last bottom; and means for independently actuating the lasting plates for the purpose described.

- 50 82. In a lasting machine the combination with toe lasting mechanism, heel lasting mechanism, a forwardly and backwardly movable support therefor, a jack post carried therewith and pressed forwardly therein, means for retracting the jack post relatively to the said support, and means for retaining the post in its retracted position, of means operative during the last portion of the backward movement of the support for automatically releasing said retaining means after the support and post have been moved backwardly far enough to insure that the shoe on the post will not be re-

turned forwardly into contact with the toe lasting mechanism.

83. A machine for lasting boots and shoes having, in combination, toe and heel lasting mechanisms, and a shoe support which is operatively connected with the heel lasting mechanism and is mounted to permit movement to effect lateral adjustment of the toe portion of the shoe carried thereby to place the median line of the forepart of the shoe in the median line of the machine and simultaneously to position the heel lasting mechanism symmetrically with relation to the median line of the heel portion of the shoe.

84. In a machine of the class described, the combination with toe lasting mechanism including wipers, of a last support arranged for adjustment relatively to such mechanism so that the direction of the longitudinal movement of the wipers will coincide with the median line of the forepart of the last, and a heel lasting mechanism the direction of the longitudinal movement of which coincides with the median line of the heel part of the last on said support in different adjustments of the support.

85. The combination with toe-lasting mechanism, of a last support arranged for adjustment to cause the median lines of foreparts of lasts having different degrees of swing to coincide with the median line of the machine, and a heel lasting mechanism having a predetermined lateral relation to the adjustable last support for longitudinal movement in a direction coinciding with the median line of the heel part of the last.

86. In a machine of the class described, the combination with toe-lasting mechanism including wipers, of a last support arranged for relative adjustment to such mechanism so that the direction of the longitudinal movement of the wipers will coincide with the median line of the forepart of the last, and means for adjustably limiting such lateral movement to positions equidistant from the median line of the machine.

87. The combination with toe-lasting mechanism, of a last support arranged for adjustment to cause the median line of foreparts of lasts having different degrees of swing to coincide with the median line of the machine, and devices for limiting such lateral movement toward opposite sides of the median line and automatically locking the support when it reaches the limit of its movement.

88. The combination with suitable operating mechanism, of longitudinally movable toe lasting mechanism and a heel lasting mechanism which are mounted for relative lateral adjustment to cause the direction of the longitudinal movement of each end lasting mechanism to coincide with the median line of the adjacent end portion of the last,

and shoe supporting means which is laterally adjustable to coöperate with the adjusted end lasting mechanisms.

89. In a machine of the class described, 5 toe and heel lasting mechanisms which are mounted for movements longitudinally and are relatively adjustable laterally into positions to cause their longitudinal movements to take place in converging paths coinciding 10 substantially with the median lines of the foreparts and heel parts of right and left crooked lasts, and toe and heel supports which are relatively adjustable laterally.

90. In a machine of the class described, 15 toe and heel lasting mechanisms which are mounted for movements longitudinally and are relatively adjustable laterally into positions to cause their longitudinal movements to take place in converging paths coinciding 20 substantially with the median lines of the foreparts and heel parts of right and left crooked lasts, and adjustable means for limiting lateral movement in either direction according to the crookedness of the right 25 and left lasts being worked upon.

91. In a machine of the class described toe and heel lasting mechanisms which are mounted for movements longitudinally of the machine and for additional bodily adjustment to change their relative lateral positions in the machine and also the direction of the longitudinal movement of one of said mechanisms.

92. In a lasting machine the combination 35 with the movable head and the limiting stops therefor of the latch 11 guided in the head and beveled to ride upon and then interlock with the stop, and means for lifting the latch.

93. In a lasting machine the combination 40 with the movable head, the limiting stops therefor and the latch 11 guided in the head and beveled to ride upon and then interlock with the stop, of means to be engaged by 45 the operator for effecting movement of the head, and a latch lifter arranged to be manipulated simultaneously with the said means to free the latch from the stop.

94. A lasting machine, having in combination, last supporting means, toe-lasting mechanism, heel-lasting mechanism, and connected means arranged to permit angular adjustment of the last to position its forepart symmetrically with relation to the toe-lasting mechanism and simultaneously to effect a different angular adjustment of the heel-lasting mechanism into symmetrical relation to the heel part of the last.

95. A lasting machine, having in combination, toe lasting mechanism, last supporting means, and heel-lasting mechanism organized to permit angular adjustment of the last and the heel-lasting mechanism simultaneously about different centers which are 60 so related that the heel-lasting mechanism is

positioned symmetrically with relation to the median line of the heel part of the last when the last is adjusted to place its forepart in symmetrical relation to the toe-lasting mechanism. 70

96. A lasting machine, having in combination, last supporting means, toe-lasting mechanism, and heel-lasting mechanism, said parts being arranged for lateral adjustment of the last about a center substantially at the toe end of the last and adjustment of the heel-lasting mechanism about a center substantially at the intersection of the median line of the forepart and the median line of the heel part of the last. 75

97. In a lasting machine, shoe supporting means, heel-lasting means, and connected means which permits simultaneous adjustment of the shoe and of the heel lasting means about different centers. 80

98. A lasting machine having, in combination, last supporting means, toe-lasting mechanism, heel-lasting mechanism, and means for effecting angular adjustment of the last laterally with relation to the toe-lasting mechanism and simultaneously effecting an angular adjustment of the heel-lasting mechanism laterally with relation to the last. 85

99. A lasting machine having, in combination, last supporting means, toe-lasting mechanism, heel-lasting mechanism, and means for effecting angular adjustment of the last laterally with relation to the toe-lasting mechanism and effecting a lateral adjustment of the heel-lasting mechanism through the same distance and simultaneously effecting an angular adjustment thereof with relation to the last. 95

100. A lasting machine having, in combination, last supporting means, and toe and heel lasting mechanisms, said machine being organized to permit relative angular lateral adjustment of the toe-lasting mechanism and the last and simultaneously to effect a relative angular lateral adjustment between the heel lasting mechanism and the last on a radius of different length. 100

101. A lasting machine, having, in combination, toe lasting mechanism, last supporting means, and heel lasting mechanism, said machine being constructed and arranged for effecting simultaneous differential adjustment of the last and one of said lasting mechanisms laterally for the purpose described. 110

102. A lasting machine, having, in combination, a toe lasting mechanism which tends to displace a shoe rearwardly, a rest for the forepart of the shoe which occupies a substantially constant normal lateral relation to the toe lasting mechanism, and means to restrain the shoe from rearward displacement by the lasting mechanism, which means is angularly movable laterally to adapt its 120

- position to that of the heel ends of right and left crooked lasts.
103. A lasting machine having, in combination, toe lasting mechanism, last supporting means including a toe rest having a normal central position and a heel rest which is movable laterally about a pivot located between the two rests to shift the forepart of the last into symmetrical lateral relation to the toe lasting mechanism, said machine having provision for limited free movement of the shoe engaging portion of the toe rest with and by the shoe to facilitate adjustment of the shoe by the heel rest. 70
104. A lasting machine having, in combination, toe lasting mechanism, last supporting means including a toe rest having a normal central position and a heel rest which is movable laterally about a pivot located between the ends of a last when supported on said rests to shift the fore part of the last into symmetrical lateral relation to the toe lasting mechanism, the portion of the shoe in engagement with said toe rest being movable laterally to facilitate adjustment of the shoe by the heel rest. 75
105. A lasting machine having, in combination, toe lasting mechanism, last supporting means including a toe rest located in the median line of the machine, and a heel rest movable about a pivot located between the ends of the last to shift the fore part into symmetrical lateral relation to the toe lasting mechanism, and heel lasting mechanism movable with said heel rest. 80
106. In a lasting machine, a swinging support carrying a jack post, a plate on said support carrying heel lasting devices, means to slide said plate in said swinging support, and means to lock said plate in its adjusted position in said support to adapt the heel lasting devices to the length of the last. 85
107. A lasting machine, having in combination, toe lasting mechanism, heel lasting mechanism, and shoe supporting means, said machine having provision for lateral curvilinear adjustment of the heel lasting mechanism and the last supporting means with relation to the toe lasting mechanism. 90
108. A lasting machine having, in combination, a shoe support, heel lasting mechanism, toe lasting mechanism, and means for actuating each of said mechanisms, said parts being constructed and mounted for relative angular lateral positioning movement to arrange them for the end lasting mechanisms to be actuated, respectively, in the directions of the median lines of the fore parts and the heel parts of right and left crooked lasts. 95
109. A machine adapted for lasting shoes on crooked lasts having, in combination, means adapted to support a crooked last with the median line of one end part of the shoe in the median line of the machine, and end lasting mechanism for the other end part of the shoe, arranged for angular adjustment to aline it with the median line of said other part of the shoe which it is to operate upon. 100
110. A machine adapted for lasting shoes on crooked lasts having, in combination, toe lasting mechanism arranged to maintain a fixed lateral angular position with relation to the median line of the machine, and means for supporting a crooked last with the median line of its fore part in alinement with said median line of the machine, a heel lasting mechanism arranged for lateral angular adjustment into alinement with the median line of the heel part of the last, and means arranged to actuate the heel lasting mechanism in the direction of the median line of the heel part of the last. 105
111. A machine adapted for lasting shoes on crooked lasts having, in combination, a toe lasting mechanism movable in the median line of the machine, means for supporting a shoe with the median line of the fore part of a crooked last in the median line of the machine, a heel lasting mechanism angularly movable laterally to aline it with the median line of the heel part of the last whether a right or a left, and means for actuating the heel lasting mechanism in said median line of the heel part of the last. 110
112. A machine adapted for lasting shoes on crooked lasts having, in combination, means for supporting shoes with the median lines of the fore parts of crooked right and left lasts in the same relation to the machine, and means for lasting the heel part of the shoe constructed and arranged for angular adjustment to position it with its line of advance movement in the median line of the heel portion of either last. 115
113. A machine adapted for lasting shoes on crooked lasts having, in combination, means for supporting shoes with the median line of one end portion of a right crooked last in the same relation to the median line of the machine as the corresponding end portion of a left crooked last, and lasting mechanism for the other end portion of the shoe constructed and arranged for adjustment into alinement with the median line of said other end portion of either the right or the left last. 120
114. In a lasting machine, the combination with end lasting mechanism, of a transversely movable last support arranged to properly position the end of a crooked last on said support with relation to said mechanism, and other end lasting mechanism for the opposite end of said last having a transverse movement with said last support. 125
115. A lasting machine, having in combination, toe lasting mechanism, heel lasting mechanism, and shoe supporting means, said machine having provision for relative 130

adjustment of the toe lasting mechanism and heel lasting mechanism about a center located below the last to permit said mechanisms to act uniformly along the sides of the 5 fore parts and heel parts of right and left shoes on crooked lasts.

116. A lasting machine having, in combination, a toe lasting mechanism laterally adjustable about a pivot and a heel lasting 10 mechanism also laterally adjustable about a pivot which occupies a different relation

longitudinally of the shoe to the heel lasting mechanism from the relation occupied by the first-mentioned pivot to the toe lasting mechanism.

15

In testimony whereof I have signed my name to this specification in the presence of two subscribing witnesses.

MATTHIAS BROCK.
